FREQUENCY CHANGING SYSTEM FOR HIGH FREQUENCY SIGNALING APPARATUS

Louis A. Gebhard, Washington, D. C.

Application December 6, 1932. Serial No. 645,961

14 Claims. (Cl. 171—242)

(Granted under the act of March 3, 1883, as amended April 30, 1928; 370 O. G. 757)

My invention relates broadly to high frequency transmitters and more particularly to frequency adjusting means for high frequency signaling systems.

One of the objects of my invention is to provide an improved construction of frequency changing apparatus for high frequency signaling systems by which rapid change in the operating frequency may be effected and high efficiency in the signaling apparatus obtained.

Another object of my invention is to provide a construction of magnetically and electrically shielded frequency changing apparatus for high frequency signaling systems in which changes in frequency may be rapidly effected while maintaining a high degree of efficiency in the signaling apparatus.

Still another object of my invention is to provide a compact construction of frequency changing apparatus for high frequency signaling systems in which inductance coils of selected frequency characteristics are mounted on a stationary frame structure adjacent a switching mechanism for completing connection between selected inductance units and associated oscillation circuits with a minimum length of leads for avoiding losses and maintaining a high degree of efficiency in the signaling system.

A further object of my invention is to provide a construction of electrically shielded drum enclosing a multiplicity of inductance units of different frequency characteristics with means for electrically shielding adjacent inductance units with switching means coacting with the inductance units for establishing electrical connection between a selected inductance unit and associated oscillation circuits while maintaining a high degree of efficiency in the operation of the signaling apparatus.

A still further object of my invention is to provide a construction of signaling apparatus in which a switching system is mounted for rotative adjustment in an annular path within a multiplicity of inductance units of different frequency characteristics for establishing electrical connection between an oscillation circuit and a selected inductance unit, the inductance units being electrically and magnetically shielded for obtaining maximum efficiency in the operation of the signaling apparatus.

Another object of my invention is to provide a construction of electrically shielded drum forming mounting means for a multiplicity of inductance units of different frequency characteristics, the inductance units being disposed in a path

about a switching apparatus which is adapted to be adjusted in a zone within the path of the several inductance units for selectively connecting an inductance unit of particular frequency characteristic with an associated oscillation system. 60

Other and further objects of my invention reside in an improved system of electrically and magnetically shielded inductance units in a high frequency signaling system as set forth more fully in the specification hereinafter following by reference to the accompanying drawings, in which:

Figure 1 is a longitudinal sectional view taken on line 1—1 of Fig. 2; Fig. 2 is a transverse, vertical sectional view taken on line 2—2 of Fig. 1; Fig. 3 is a similar view taken on line 3—3 of Fig. 1; Fig. 4 is a horizontal sectional view taken on line 4—4 of Fig. 3; Fig. 5 is a fragmentary front elevation of a portion of the casing; Fig. 6 is a detailed sectional view showing more particularly the arrangement of the contact brushes; Fig. 7 is a fragmentary sectional view on line 7—7 of Fig. 4, showing the means employed to stop the rotation of the inner shell; Fig. 8 is a fragmentary side elevation over a portion of the shell retaining ring; and Fig. 9 is a detailed vertical sectional view taken on line 9—9 of Fig. 8. 70 75 80

One of the difficulties met with in a transmitter having a wide frequency band is due to the coupling, both electric and magnetic, between the coils used for different frequency ranges 85 that are part of the input and output circuits of the amplifiers. Generally, but one coil is used at a time, but other coils must be available and must be placed in close proximity to the coil in use in order that the transmitter may be 90 compact and in order that the length of the necessary leads are not so excessive as to prohibit operation at high frequencies. Of course, the coils may be of the plug-in type, in which case but one coil is in use in the transmitter 95 at one time, the other coils being kept about the radio room adjacent the transmitter. This is an unsatisfactory arrangement, it being far more desirable to incorporate the coils in the transmitter and provide a switching system to 100 substitute quickly one coil for another in the circuit. Quick interchange is impossible with plug-in coils.

The coils must not only be shielded magnetically, but must also be shielded electrically. Former shielding systems have not provided perfect shielding from an electrical standpoint. The contacts of the coils project out into the space where the switching is effected. Imperfect shielding results in that there is a certain amount 105 110

of capacity between these coil contacts and as a result of this capacity, considerable energy may be transferred from a coil in use to one which is not in use. The system shown in the accompanying figures is arranged to reduce this electric coupling to a minimum. Adequate magnetic shielding is also provided in this system. The system also provides a number of unique constructional features.

- 10 The coils are shown at 1 mounted in a circular arrangement. These coils are of different frequency characteristics and instead of being a single coil may comprise several coils adjacent to each other or coaxial with each other. Each 15 coil unit 1 is contained in a compartment formed by two concentric metal cylinders 2 and 3. The ends of these cylinders are closed by means of annular metallic plates 4 and 4'. Partitions 5 extending radially divide the space into the 20 required number of compartments. Any number of compartments or any number of coils may be used. Members 5 are turned over at right angles at their outer edges as shown at 6 so as to permit fastening of the cylinder 2. 25 They are also turned over at right angles at their outside edges as shown at 7 and 7' so as to permit fastening of the sides 4 and 4' to make the structure rigid. The outer cylinder 3 and through it the rest of the structure, is 30 supported by angle members 8 and 8' from the framework on the radio transmitter shown at 9, 9', 10 and 10'. The front panel of the high frequency transmitter is shown at 11, the rear panel at 11'. Inner cylinder 2 is arranged to turn 35 in bearings formed by the annular metallic plates 4 and 4'. Ring members 12 and 12' serve to hold cylinder 3 in the bearings. The ring members 12 and 12' consist of rings made of flexible metal material fastened to annular metallic plates 40 4 and 4' by means of screws 13. The inner peripheral edges of these rings are split as shown at 14 so as to provide good contact to the ends of cylinder 2, thus completing the connection of the shielding and providing effective means of 45 shielding. The ends of cylinder 2 are closed off by members 15 and 15'. Members 15 and 15' are fastened to cylinder 2 by means of screws 2a extending through cylinder 2 and into the edges of members 15 and 15'. At the centers 50 of members 15 and 15' there is mounted a shaft 16 by means of bearing members 17 and 17' which are secured to the shaft by means of pins 18 and 18'. Bearing members 17 and 17' are fastened to members 15 and 15' by means of 55 screws 17a and 18a. Members 15 and 15' are made of suitable insulating material and on their outer surface are mounted collector rings 19, 19', 20 and 20'. These rings are secured to members 15 and 15' by means of screws 15a and 60 15a'. Connections are provided to these rings at 21, 21', 22 and 22'. An insulating member 23 extends between end members 15 and 15'. The member 23 carries contacts 24 which pass 65 through a narrow slot 25 in cylinder 2 engaging with the oppositely directed brushes 26 mounted on the inductance coils 1. Slot 25 does not extend over the full length of the cylinder but only between points 27 and 27'. The electrostatic shields or compartment dividers 5 are provided with narrow slots as shown at 28 so as 70 to permit passage of contacts 24 as the drum 2 is rotated for the selection of an inductance unit. These slots are very narrow but fully wide enough to permit the contacts 24 to pass through. 75 If desired these slots may be arranged with a

mechanism which will close after the contact has passed through. Ordinarily, however, the slots are so narrow as to provide no serious amount of electric coupling between the adjacent coils. It will be noted that as cylinder 2 rotates, the slot 25 follows so that it is always in the position of the used coil, all other coils being effectively shielded from the coil in use.

Connections 29, 29', 30 and 30' are provided between the collector ring binding posts 21, 21', 22 and 22' and the binding posts 31 of contacts 24. Connection is made between collector rings 19, 19', 20 and 20' and the external circuit by means of brushes 32, 32', 33 and 33' mounted on insulating members 34, 34', which are supported by means of spacers 35 and 35', 36 and 36' on side members 4 and 4' by means of screws or bolt members. A stopping device or pawl 37 is mounted on insulating member 34 by means of screws or bolt members. This pawl or device 37 carries a tooth at the end of a flat spring member which engages with detents 38 in member 15. This stopping mechanism serves to arrest rotation of the cylinder in the proper positions to engage the coil contacts.

Binding posts 39 and 39' are provided for connections to the external oscillator circuits which are arranged immediately adjacent the frequency changing apparatus for avoiding losses inherent with long leads.

Coils 1 may be supported in their compartments in any desirable way. One method is shown by the use of insulating members 40 and 41 disposed at right angles to each other and secured by screws 42 between the metallic plates 4 and 4'. The coils 1 are spaced from the walls forming the compartments. It will be observed that the compartments are closed on the six sides thereof by metallic walls which serve to electrically and magnetically shield each of the inductance units from each other and from the influence of external electrostatic or electromagnetic fields. The metallic enclosures within which each of the inductance units are mounted serve to confine the electrostatic and electromagnetic fields of each inductance unit to the individual compartments thereby enabling the apparatus to be compactly assembled without causing mutual electrostatic or electromagnetic interference and without becoming a source of undesired and interfering electromagnetic or electrostatic fields. The shaft 16 is caused to rotate by means of control 43 located on the front of the front panel. The dial 44 indicates the particular coil in the circuit by numerals engraved on the surface as shown at 45 which can be seen through aperture 46 in the front panel 11. The coil contacts may consist of brushes 47, 47' fastened to a member 48 by means of screws 49, 49'. Member 48 is fastened to the turn of the inductance coil in a pre-determined position by soldering or other means.

It will be understood that many modifications in the structure of my invention may be made. For instance, the brushes 26 instead of being mounted on the coil may be mounted on the moving member and the contacts mounted on the inductance coil. This arrangement is in general undesirable, however, due to the fact that the slots 28 can be made narrower if the brushes are placed on the coil and the contacts allowed to rotate thereby avoiding losses due to electrostatic coupling. The brushes 26 need not be mounted directly on the coil but can be mounted on an insulating member supported in any desirable way but independent from the coil. The

150

coil itself may take any form desired and may be a series of windings or a single winding. The insulating strip supporting the contacts 24 referred to may also be mounted on the coil if desired.

Another modification may be made by eliminating the portion of the shaft 16 back of and beyond the bearing member 17 which also eliminates bearing member 18 and the associated parts. If this is done 15' may be cut out at the center to allow an access aperture for assembly, repair and maintenance of the apparatus.

The structure of my invention permits rapid transfer of connections between the oscillatory system and a selected inductance coil while preserving maximum shielding for the several inductance coils. Both electric and magnetic shielding is insured in the apparatus of my invention regardless of the fact that rapid change of the selected inductance units may be made.

20 The metallic rotatable cylinder 2 establishes electrical connection with the edges of the annular metallic plates 4 and 4'. As the cylinder 2 rotates, the continuity of the metallic shielding on all four sides of the inductance coil is maintained as electrical connection is made at all times with the edges of radially extending shields 5 at the same time that cylinder 2 makes electrical connection with the edges of annular metallic plates 4 and 4'. Extremely short connections are made to the adjacent oscillation circuits. While I have indicated such connections schematically as wired elements, it is understood that such connections are in the form of busses of relatively large surface area having low resistance to radio frequency currents.

35 I have described my invention in certain preferred embodiments, but I desire that it be understood that modifications may be made by those skilled in the art and that no limitations upon my invention are intended other than are imposed by the scope of the appended claims.

40 The invention described herein may be manufactured and used by or for the Government of the United States of America for governmental purposes without the payment of any royalty thereon or therefor.

45 What I claim as new and desire to secure by Letters Patent of the United States is as follows:

50 1. In a frequency changing apparatus, a supporting structure, a metallic housing carried by said supporting structure, a plurality of electrically shielded metallic compartments formed in said housing, insulated supports in each of said compartments, inductance units of different frequency characteristics carried by said supports and having taps thereon, said inductance units being spaced from the walls of said metallic compartments, a rotatable metallic cylinder disposed concentrically within said metallic housing, contact members extending through apertures formed in said rotatable cylinder for establishing connection with selected taps on said inductance units, and means for angularly shifting said cylinder for correspondingly establishing connection with a selected inductance unit.

55 2. In a frequency changing apparatus, a supporting structure, a metallic housing carried by said supporting structure, a multiplicity of radially disposed compartments in said metallic housing, inductance units of different frequency characteristics mounted in said compartments and spaced from the walls of said compartments, a rotatable metallic cylinder forming the inner wall of said compartments and concentrically disposed with respect to said metallic housing

and movable within said metallic housing, and switching means carried by said rotatable metallic cylinder for establishing connections with selected inductance units.

3. In a frequency changing apparatus, a supporting frame, a metallic housing carried by said supporting frame, a multiplicity of electrostatically shielded compartments disposed radially with respect to said metallic housing, insulated supports extending through each of said compartments, inductance units of different frequency characteristics carried by the supports in said compartments, a cylindrical metallic shield forming the inner wall of said metallic housing, contact members projecting through said cylindrical metallic shield, and means for rotatably moving said shield for establishing electrical connections between said contacts, and taps on selected inductance units in said compartments.

4. Frequency changing apparatus comprising a frame structure, a metallic housing carried by said frame structure, a multiplicity of radially disposed electrostatically shielded compartments in said housing, inductance units of different frequency characteristics mounted in said compartments, a cylindrical electrostatic shield forming the inner wall of said housing, bearings for mounting said cylindrical electrostatic shield for rotative movement within said housing, an actuator for imparting angular movement to said cylindrical electrostatic shield, and a multiplicity of contact members projecting through said cylindrical electrostatic shield for establishing connection with selected inductance units in said compartments as said actuator is rotated.

5. In a frequency changing apparatus, a supporting structure, a metallic housing carried by said supporting structure, a multiplicity of radially disposed flat plate members constituting shields dividing said housing into compartments, inductance units of different frequency characteristics mounted in said compartments in spaced relation to said shields, a rotatable metallic cylinder constituting the inner wall of said compartments, switching means located within said metallic cylinder and means for shifting said metallic cylinder to different angular positions for establishing connection between said switching means with selected inductance units in said compartments.

6. In a frequency changing apparatus, a supporting structure, a metallic housing carried by said supporting structure, said housing being constituted by a substantially toroidal shaped electrostatically shielded container, a cylindrical member forming the inner wall of said toroidal container, electrostatically shielded compartments disposed in said toroidal container, inductance units of different frequency characteristics in each of said compartments, and switch elements projecting through said cylindrical member for establishing electrical connection with selected inductance units, and means for angularly adjusting the position of said switch elements for correspondingly selecting the inductance units.

7. In a frequency changing apparatus, a cylindrical metallic housing, a frame structure supporting said housing, a central cylindrical member disposed concentrically within said housing and rotatably adjustable with respect thereto, a plurality of radially extending electrostatic shields disposed between said cylindrical housing and said cylindrical member and defining elec-

- trostatically shielded compartments, inductance units of different frequency characteristics disposed in each of said compartments and spaced from the walls thereof, switching means projecting through said cylindrical member and insulated therefrom for establishing electrical connection with a selected inductance unit, and means for rotatably adjusting the position of said cylindrical member for correspondingly establishing connection between said switching means and a selected inductance unit. 80
8. Frequency changing apparatus comprising a supporting structure, a toroidal metallic chamber carried by said supporting structure, a rotatable member having a cylindrical wall forming the inner closure for said toroidal chamber, electrostatic shields extending radially of said toroidal chamber and forming electrostatically shielded compartments within said toroidal chamber, inductance units of different frequency characteristics mounted in each of said compartments, switching means extending through said cylindrical wall for establishing connection with a selected inductance unit, and means for shifting said switching means to a selected inductance unit while maintaining the electrostatic isolation of inductance units. 85
9. In a frequency changing apparatus, a supporting structure, a metallic casing carried by said supporting structure, a plurality of inductance units of different frequency characteristics mounted interiorly of said metallic casing and spaced from the wall formed by said casing, a cylindrical member constituting the inside wall of said casing, means for journaling said cylindrical member for rotation with respect to said casing, and switching means extending through said cylindrical member and insulated therefrom for establishing selective electrical connection with a selected inductance unit within said chamber. 90
10. In a frequency changing apparatus, a supporting structure, a metallic casing carried by said supporting structure, a plurality of inductance units of different frequency characteristics mounted interiorly of said metallic casing in spaced relation to the wall of said casing, a cylindrical member constituting the inside wall of said casing, an insulated end wall closing each end of said cylindrical member, collector rings mounted on said end walls, contact members extending through said cylindrical member and electrically insulated therefrom for establishing connection with a selected inductance unit, connections between said contact members and said collector rings, and means passing through said end walls for moving said contact members for establishing connection with a selected inductance unit. 95
11. In a frequency changing apparatus, a supporting structure, a metallic casing carried by said supporting structure, a plurality of inductance units of different frequency characteristics mounted interiorly of said metallic casing and spaced from the wall of said casing, a cylindrical member constituting the inside wall of said casing, an annular plate connected to each end of said casing and extending across the peripheral edge of said cylindrical member for rotatably journaling said cylindrical member within said casing, an insulated end plate disposed laterally across each end of said cylindrical mem- 100
- ber, collector rings carried by said insulated end plates, contacts electrically connected with said collector rings and projecting laterally through one side of said cylindrical member and electrically insulated therefrom for establishing selective connection with said inductance units, and means connected with said insulated end plates for imparting angular movement to said cylindrical member for correspondingly shifting said contacts for rendering selected inductance units electrically effective. 105
12. Frequency changing apparatus comprising a toroidal shaped casing, a multiplicity of inductance units of different frequency characteristics disposed in electrostatically shielded compartments within said casing and spaced from the walls thereof, a switching unit constituted by a cylindrical member extending concentrically through said toroidal casing, and switching elements projecting through one wall of said cylindrical member and electrically insulated therefrom for establishing selected electrical connection with a particular inductance unit as said cylindrical member is rotatably adjusted within said toroidal casing. 110
13. Frequency changing apparatus comprising a supporting frame, a metallic housing carried by said supporting frame comprising a metallic channel shaped structure having a cylindrical aperture extending through the center thereof, a metallic cylindrical member extending through the aperture in said housing and forming the inner wall of the channel shaped structure, a plurality of radially extending electrostatic shields disposed in said structure and defining compartments in said channel shaped housing, inductance units of different frequency characteristics disposed in said compartments, contact elements extending through said cylindrical member for establishing electrical connection with selected taps on said inductance units, and means for rotatably moving said cylindrical member and the contacts projecting therethrough for selecting a particular inductance unit and rendering the same effective while electrostatically shielded from others of said inductance units. 115
14. Frequency changing apparatus comprising a supporting frame, a metallic housing carried by said supporting frame comprising a metallic channel shaped structure having a cylindrical aperture extending through the center thereof, a metallic cylindrical member extending through the aperture in said housing and forming the inner wall of the channel shaped structure, a plurality of radially extending electrostatic shields disposed in said structure and defining compartments in said channel shaped housing, inductance units of different frequency characteristics disposed in said compartments, an insulated support disposed within said cylindrical member, contact elements carried by said insulated support and projecting through one wall of said cylindrical member for establishing electrical connection with said inductance units, said radially extending shields each being slotted adjacent said cylindrical member for permitting the passage of said contact elements therethrough for establishing electrical connection with selected inductance units as said selected member is rotatably adjusted in position within said housing. 120
15. Frequency changing apparatus comprising a supporting frame, a metallic housing carried by said supporting frame comprising a metallic channel shaped structure having a cylindrical aperture extending through the center thereof, a metallic cylindrical member extending through the aperture in said housing and forming the inner wall of the channel shaped structure, a plurality of radially extending electrostatic shields disposed in said structure and defining compartments in said channel shaped housing, inductance units of different frequency characteristics disposed in said compartments, an insulated support disposed within said cylindrical member, contact elements carried by said insulated support and projecting through one wall of said cylindrical member for establishing electrical connection with said inductance units, said radially extending shields each being slotted adjacent said cylindrical member for permitting the passage of said contact elements therethrough for establishing electrical connection with selected inductance units as said selected member is rotatably adjusted in position within said housing. 125
16. Frequency changing apparatus comprising a supporting frame, a metallic housing carried by said supporting frame comprising a metallic channel shaped structure having a cylindrical aperture extending through the center thereof, a metallic cylindrical member extending through the aperture in said housing and forming the inner wall of the channel shaped structure, a plurality of radially extending electrostatic shields disposed in said structure and defining compartments in said channel shaped housing, inductance units of different frequency characteristics disposed in said compartments, an insulated support disposed within said cylindrical member, contact elements carried by said insulated support and projecting through one wall of said cylindrical member for establishing electrical connection with said inductance units, said radially extending shields each being slotted adjacent said cylindrical member for permitting the passage of said contact elements therethrough for establishing electrical connection with selected inductance units as said selected member is rotatably adjusted in position within said housing. 130
17. Frequency changing apparatus comprising a supporting frame, a metallic housing carried by said supporting frame comprising a metallic channel shaped structure having a cylindrical aperture extending through the center thereof, a metallic cylindrical member extending through the aperture in said housing and forming the inner wall of the channel shaped structure, a plurality of radially extending electrostatic shields disposed in said structure and defining compartments in said channel shaped housing, inductance units of different frequency characteristics disposed in said compartments, an insulated support disposed within said cylindrical member, contact elements carried by said insulated support and projecting through one wall of said cylindrical member for establishing electrical connection with said inductance units, said radially extending shields each being slotted adjacent said cylindrical member for permitting the passage of said contact elements therethrough for establishing electrical connection with selected inductance units as said selected member is rotatably adjusted in position within said housing. 135
18. Frequency changing apparatus comprising a supporting frame, a metallic housing carried by said supporting frame comprising a metallic channel shaped structure having a cylindrical aperture extending through the center thereof, a metallic cylindrical member extending through the aperture in said housing and forming the inner wall of the channel shaped structure, a plurality of radially extending electrostatic shields disposed in said structure and defining compartments in said channel shaped housing, inductance units of different frequency characteristics disposed in said compartments, an insulated support disposed within said cylindrical member, contact elements carried by said insulated support and projecting through one wall of said cylindrical member for establishing electrical connection with said inductance units, said radially extending shields each being slotted adjacent said cylindrical member for permitting the passage of said contact elements therethrough for establishing electrical connection with selected inductance units as said selected member is rotatably adjusted in position within said housing. 140
19. Frequency changing apparatus comprising a supporting frame, a metallic housing carried by said supporting frame comprising a metallic channel shaped structure having a cylindrical aperture extending through the center thereof, a metallic cylindrical member extending through the aperture in said housing and forming the inner wall of the channel shaped structure, a plurality of radially extending electrostatic shields disposed in said structure and defining compartments in said channel shaped housing, inductance units of different frequency characteristics disposed in said compartments, an insulated support disposed within said cylindrical member, contact elements carried by said insulated support and projecting through one wall of said cylindrical member for establishing electrical connection with said inductance units, said radially extending shields each being slotted adjacent said cylindrical member for permitting the passage of said contact elements therethrough for establishing electrical connection with selected inductance units as said selected member is rotatably adjusted in position within said housing. 145
